(57) **CLAIM**

The ornamental design for a magnetic drinking cup, as shown and described.

DESCRIPTION

FIG. 1 is a front elevational view of a magnetic drinking cup, shown in a first configuration and fully assembled;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a front elevational view, shown in a second configuration with the top lid in isolation for clarity of disclosure;

FIG. 10 is a rear elevational view thereof;

FIG. 11 is a left-side elevational view thereof;

FIG. 12 is a right-side elevational view thereof;

FIG. 13 is a top plan view thereof;

FIG. 14 is a bottom plan view thereof;

FIG. 15 is a first perspective view thereof;

FIG. 16 is a second perspective view thereof;

FIG. 17 is a front elevational view, shown in a third configuration with the bottom lid in isolation for clarity of disclosure;

FIG. 18 is a rear elevational view thereof;

FIG. 19 is a left-side elevational view thereof;

FIG. 20 is a right-side elevational view thereof;

FIG. 21 is a top plan view thereof;

FIG. 22 is a bottom plan view thereof;

FIG. 23 is a first perspective view thereof;

FIG. 24 is a second perspective view thereof; and,

FIG. 25 is a third perspective view thereof.

(Continued)

The broken lines shown in the drawings are for the purpose of illustrating portions of the article and form no part of the claimed design.
